UNITED STATES PATENT OFFICE.

NATHANIEL A. BOYNTON, OF NEW YORK, N. Y.

FIRE-PLACE HEATER.

SPECIFICATION forming part of Letters Patent No. 444,987, dated January 20, 1891.

Application filed May 11, 1885. Serial No. 165,078. (No model.)

To all whom it may concern:

Be it known that I, NATHANIEL A. BOYNTON, of the city, county, and State of New York, have invented certain new and useful improvements in Fire-Place Heaters, of which the following is a full, clear, and exact description.

This invention relates to that description of fire-place heaters commonly known as "Baltimore fire-place heaters," in which the body of the heater, that is of a close or stove-like construction and is generally furnished with doors and transparencies in front, is combined with and arranged to project largely in front of a frame or plate of any desired pattern, ornamental or otherwise, made to close in the fire-place about the body and base of the heater.

My invention consists in a certain combination of flues or passages for the escaping products of combustion with the body of the heater, its base, and the fire-place frame or plate inclosing the rear portion of the body and base of the heater, including flues arranged down either side of the body in front of said plate or frame, whereby the heat is more thoroughly utilized within the apartment in which the heater is situated.

Reference is to be had to the accompanying drawings, forming part of this specification, in which similar letters of reference indicate corresponding parts in all the figures.

Figure 1 represents a horizontal section of the heater upon the line *x x* in Fig. 2. Fig. 3 is a vertical section of the same on the line *y y* in Fig. 1, and Fig. 3 is a vertical section upon the line *z z* in Fig. 2.

A is the body, fire-chamber, or fire-pot of the heater, arranged to occupy a central position in the heater and of the usual or any suitable construction; B, its fuel cylinder or feeder; C, its grate, and D its base, inclosing the ash-pit *b*.

E is the plate, fire-board, or frame which closes in the fire-place about the body and base of the heater, and in front of which a large or the front portion of the body of the heater projects, as usual.

G G are tubes or flues arranged down either side of the body A in front of the plate or frame E. These front and exposed side flues G G connect at their upper ends, as by

branches *c c*, with the upper portion of the body A, and at their lower ends with side flues *d d*, arranged in the base D on opposite sides of the ash-pit *b*, and from which upward-escape flues *e e*, at the rear ends of the flues *d d*, preferably merging into a single flue above, project to carry off the escaping gaseous products of combustion and establish the necessary draft.

By the arrangement of the flues G G down or on opposite sides of the body A of the heater, outside of the plate or frame E, the highly-heated gases of the products of combustion as they leave the fire-chamber and body A will contribute very sensibly by the exposed position of said flues to warm the apartment in which the heater is situated, and said flues by their prominence will also give a more ornamental appearance to the heater.

The fuel is or may be supplied to the feeder B by opening a door *g*, arranged to close the mouth end of a hood *h* on the cover *i* of the feeder beneath a plate *k*, which projects from the front of the frame or plate E of the heater.

It should here be observed that the tubes G G are both purely downtake-flues and that they stand out well in front of the fire-board E, being wholly in front thereof; also, that the lower side flues *d d* constitute two horizontal ground-flues leading under and behind the fire-board to a rear uptake inverted-Y flue, formed by the uptake-flues *e e* merging into a single one, as described. This combination and arrangement of the flues, fire-pot, and fire-board makes the fire-place heater to essentially differ from other fire-place heaters, in which the gaseous products of combustion are allowed to escape directly from the fire-pot or body of the heater through flues in rear of the fire-board, and it differs also from other fire-place heaters provided with various ascending and descending flues, including fire-place heaters provided with a fire-board and heat-radiating side columns forming part of the indirect-draft flue and arranged to project only partly in front of the fire-board and constituting the one a downtake and the other an uptake-flue for use in connection with a heat-radiating box having deflectors to control the current. In my fire-

place heater, as hereinbefore described, the flues G G are both downtakes, and wholly stand out in front of the fire-board, and the escaping heat is concentrated in front for use in the apartment in which the heater stands.

I do not claim as my invention any of the parts herein described, separately considered, and disclaim each and all of the several inventions shown and described in the following patents, to wit: the magazine-stove in Patent No. 31,480, issued February 19, 1861, to S. T. Savage, in which a base-burning chamber and external case have combined with them specially-arranged partitions and parts, whereby an indirect draft is produced around the front, sides, and back of the stove; the heating-stove described in Patent No. 24,241, to G. H. Russell, May 31, 1859, in which an inner fire-drum, cold-air base, vertical side pipes, and elbows, with dampers and cylindrical cover or top drum, with various chambers and connecting-tube, horizontal air-space, and other parts, including front vertical register-pipes, and foot-warmer connecting-pipes were used; the fire-place stove described in Patent No. 163,233, of H. P. Ohm, in which were combined deflectors, &c., with certain outstanding radiating columns only partially exposed in front and forming the one an uptake and the other a downtake; the base-burning stove shown in Reissued Patent No. 6,884, to S. B. Sexton, January 25, 1876, and having one or more side columns arranged to lead into a hollow base and connecting indirectly with the chimney-flue; the fire-place heater in Patent No. 176,970, issued May 2, 1876, to J. A. Lawson, also using side pipes in connection with a bottom flue, side bottom flues, and a back pipe extending upward and laterally and uniting above, and the base-burning fire-place heater in Patent No. 94,320, August 31, 1869, to Philip Klotz, in which vertical flue-columns terminating above in a chamber formed by a horizontal section extending laterally from the fire-chamber all around are used. In each and all of these structures the combinations shown are different from the combination which makes up my improved fire-place heater, with its two advance downtake-flues wholly in front of the fire-board, and which has for its spe-

cial object increasing the power of heat-radiation within the apartment in which the heater stands.

Having thus described my invention, I claim as new and desire to secure by Letters Patent—

1. The combination, in a fire-place heater, of a heater-frame, a fire-box, a combustion-chamber over the same, front vertically-descending flues arranged wholly in front of the frame and connected directly to the combustion-chamber, horizontal rearwardly-extending base-flues, and exit-flues or smoke-pipes. 60

2. The combination, with a heater-frame and a fire-place heater having its combustion-chamber extending in front of the frame, of direct vertical downdraft-flues located in front of the frame and connected directly to the combustion-chamber in front of the frame, independent horizontal rearwardly-extending side base-flues on each side of the heater, and exit-flues or smoke-pipes at back of the heater. 70

3. The combination, with a heater-frame and a fire-place heater, of a crown having side extensions in front of the frame, direct vertical downdraft-flues located in front of the frame, and base-flues connected by said vertical flues with the extensions and extending rearwardly to the exit-flues. 75

4. In a fire-place heater, the combination, with the body, fire-chamber A, fire-board E, and base D, of the upper side flues or branches c c, connecting with the body of the heater at its top, the exterior downtake-flues G G in advance of the fire-board and center of the body of the heater and arranged to connect the upper branch flues c c with the base D, the horizontal ground-flues d d, leading under and behind the fire-board, and the uptake and Y flue in the rear, all as herein shown and described, whereby the side downtake-flues G G have a prolonged radiating-surface extending from the top of the heater to its base, as set forth. 95
